THREAD CUTTER FOR SHUTTLES

Application filed February 21, 1931. Serial No. 517,562.

This invention relates to improvements in weft cutters for automatic looms and it is the general object of the invention to utilize concave and convex coacting members to assist in parting the weft leading from the shuttle delivery eye.

In weft replenishing looms there remains at the time of transfer a thread end which extends from the outgoing bobbin through the delivery eye and along the front wall of the shuttle to the adjacent selvage. It is desirable to remove this end prior to the succeeding pick of the shuttle in order to prevent the same from being whipped into the shed. Severing the weft is a part of the operation necessary to accomplish this result. It is an important object of my present invention to provide a shuttle with a delivery eye so formed that it will coact with a normally inoperative device at the time of transfer to force the weft issuing from the eye against a portion of the device to part the weft.

It is a further object of my present invention to provide a resiliently mounted weft parting device which shall have a rounded rear end movable into engaging relation with those portions of the delivery eye over which the weft normally extends when the shuttle is boxed for transfer. The rounded end is preferably spherical, but whatever its form, it is so shaped as to conform to a portion at least of the delivery eye. Means are also provided to permit the rounded or spherical surface to move both vertically and horizontally throughout a restricted zone of motion for the purpose of coacting with the shuttle even though the latter be slightly misplaced.

With these and other objects in view which will appear as the description proceeds, my invention resides in the combination and arrangement of parts hereinafter described and set forth in the claims.

In the accompanying drawing, wherein a convenient embodiment of my invention is set forth,

Fig. 1 is a top plan view of a shuttle and weft parter made according to my present invention, parts of the shuttle being shown in section,

Fig. 2 is an enlarged horizontal section

through the member which is independent of the shuttle and normally placed out of engaging position with the latter, and

Fig. 3 is a front elevation of the shuttle.

Referring to the drawing, I have shown a shuttle S having a weft chamber 10 in which the weft carrier 11 is normally mounted. The weft W extends from the carrier into a thread passage 12 and may be led around a guide post 13 toward a delivery eye 14. The latter may be formed substantially as shown in Figs. 1 and 3 and may have a tubular body 15 with a thread opening 16 at the top thereof as shown in Fig. 3. The eye is made of hard material, preferably metal, and has a tubular bore with surfaces or edges which, as indicated at 17 in Fig. 1, may be formed to assist in parting the weft. The surface 17 may be either a cutting edge or a slightly rounded surface.

A lever 20 may be mounted to move about a pivot 21 and is controlled by transfer mechanism indicated at 22, spring 23 tending normally to move the right hand end of the lever as viewed in Fig. 2 rearwardly.

Passing through the lever and extending rearwardly is a stem 24 having a threaded head 25 over which is threaded a tube 26. A set screw 27 holds the stem in position and affords a coarse adjustment for placing the tube 26. The threaded connection between the head and the tube may be used to give a finer setting. A hammer head 28 has a rounded preferably spherical rear end 29 which is proportioned to coact with the surface 17 of the delivery eye. The forward end of the head may have a flange 30 which engages the end wall 31 of the tube 26 to limit rearward movement of the hammer. A compression spring 32 is located between the thread head 25 and the flange 30 and tends normally to hold the hammer head in rear position but permits the latter to assume the dotted line positions shown in Fig. 2.

In operation, the transerrer arm 22 holds the lever and hammer head 28 in forward position against the action of spring 23 so that as the shuttle moves forwardly on the lay L the delivery eye will not engage the spherical end 29 of the hammer. At the time of trans-

fer, however, the arm 22 moves forwardly to permit spring 23 to move the hammer head rearwardly and the rounded end 29 of the latter will thereupon be brought into the path of movement of the delivery eye. 5 Further advance movement of the lay will effect engagement between the edge 17 and the surface 29 with resultant parting of the weft. As the exhausted bobbin leaves the 10 shuttle the weft end thereof will be free to move out of the eye and there will be no thread in the shuttle eye.

While I have shown the edge 17 as being 15 circular and formed as part of the side delivery eye, yet in its broader significance my invention contemplates the use of a surface on the shuttle across which the weft extends so shaped as to coact with the rounded hammer for the purpose of parting the weft when the hammer forces the weft against its circular or arcuate surface.

In the ordinary running of a loom the shuttle will not always be boxed in exactly 20 the same position and in order that the part- 25 er may operate with the shuttle when slightly displaced the yielding mounting set forth herein is employed. As shown in full lines in Fig. 2 the hammer head is at rest with the 30 spring 32 fully expanded. Should the shuttle be to the right or left of its normal position, however, the rounded surface of the head will cam the latter so that it will assume one or the other of the dotted line positions shown in Fig. 2. In view of the fact that the 35 surface 29 is spherical the movement from the full to the dotted line positions will not affect materially the relation between the weft parting surfaces.

From the foregoing it will be seen that I 40 have provided a simple form of thread parter wherein a rounded member is brought into contact with a second member which is concave and provided with a surface to coact with a rounded member, one of said members 45 being mounted on the shuttle and so disposed that the weft extends thereacross when the shuttle is in replenishing position. A convenient embodiment of this principle contemplates the use of the side delivery eye as the 50 concave member. It will further be seen that the member which is mounted independently of the shuttle is adapted for universal movement and that the relation of the contacting surfaces of the members is not materially 55 changed by slight displacements of the shuttle. It will also be seen that the spring 32 will permit yielding of the hammer head after the two weft parting members engage and during subsequent forward movement of 60 the lay. Variations in the force exerted by the spring 32 may be obtained by changing the relative position of the tube 26 and the head 25.

Having thus described my invention it 65 will be seen that changes and modifications

may be made therein by those skilled in the art without departing from the spirit and scope of the invention and I do not wish to be limited to the details herein disclosed, but what I claim is:

1. In weft parting mechanism for a weft replenishing loom, a shuttle having a weft delivery eye, and means to coact with the eye to part the weft.

2. In combination in a weft replenishing loom, a shuttle having a weft delivery eye formed of hard material, and means to force the weft against the eye to part said weft.

3. In combination in a weft replenishing loom having a lay, a shuttle movable forwardly with the lay and having a front delivery eye from which the weft extends, and means operative through forward movement of the lay to coact with the eye and part the weft.

4. In combination in a weft replenishing loom, a shuttle having a weft delivery eye from which weft extends and across a portion of which the weft lies, and means to engage the eye and part the weft at said portion across which the weft lies.

5. In combination in a weft replenishing loom having a lay, a weft delivery eye movable forwardly with the lay, and means mounted independently of the eye to engage the latter on transferring beats of the loom to part the weft by engagement of the eye and means.

6. In weft parting mechanism for a weft replenishing loom operating with a shuttle, 100 a pair of coacting members one concave and the other convex, one of the members mounted on the front wall of the shuttle, the weft extending across one of said members, and means to cause engagement of the members 105 to part the weft.

7. In weft parting mechanism for a weft replenishing loom operating with a shuttle, 110 a pair of coacting weft parting members one concave and mounted on the shuttle and the other convex and mounted independently of the shuttle and proportioned to enter the concave member, the weft leading from the concave member over a surface of the latter engaged by the convex member, and means to 115 effect engagement between the members to part the weft.

8. In weft parting mechanism for a weft replenishing loom operating with a shuttle, 120 a concave member carried by the front wall of the shuttle and having a portion over which the weft extends, a convex member to register with the concave member, and means to effect engagement of the members to part 125 the weft between them.

9. In weft parting mechanism for a weft replenishing loom operating with a shuttle, 130 a pair of weft parting members one of which is concave and mounted on the shuttle and the other of which is concave, the concave

member to approach the convex member, a yielding mounting for the convex member effective to yield in any angular direction relatively to the line of approach of the members, the weft extending through and across a portion of the concave member, and means to effect engagement between the members to part the weft.

10. In weft parting mechanism for a weft replenishing loom operating with a shuttle, a pair of weft parting members one of which is concave and located on the front wall of the shuttle, and the other of which is convex and proportioned to register with a surface of the concave member, the weft of the shuttle extending across one of said members, and means to effect engagement between the members to part the weft.

11. In weft parting mechanism for a weft replenishing loom operating with the shuttle, a pair of coacting weft parting members one of which is carried by the shuttle and has an arcuate surface across which the weft extends, the other member having a substantially spherical convex surface to engage the arcuate surface of the other member to part the weft.

12. In weft parting mechanism for a weft replenishing loom operating with the shuttle movable forwardly in the loom, a weft parting member carried by the shuttle, a second parting member to coact with the first named member to effect parting of the weft, a holder for the second member, and a yielding positioning element supported by the holder and contacting with the second named element and yieldable in all angular directions with respect to the forward movable shuttle.

40 13. In weft parting mechanism for a weft replenishing loom operating with the shuttle, a concave weft parting member carried by the shuttle, a second weft parting member having a convex rounded surface to engage the concave member to effect weft parting, a carrier for the second member, and a resilient connection interposed between the carrier and the second member whereby the latter is yieldable forwardly with respect to the carrier by a force derived from the shuttle, and angularly in all directions relatively to the path of movement of the member on the shuttle.

55 14. In weft parting mechanism for a weft replenishing loom operating with the shuttle, a concave weft parting member carried by the shuttle, a second weft parting member having a convex rounded surface to engage the concave member to effect weft parting, the second member being elongated in the direction of the advance of the shuttle, a holder for the second member with respect to which the latter is movable in all angular directions, a resilient element to maintain the second member in normal position, said

second member being movable with respect to the holder when engaging the concave member to accommodate different positions of the shuttle.

15. In weft parting mechanism for a weft replenishing loom operating with the shuttle, a concave weft parting member carried by the shuttle, a second weft parting member having a convex rounded surface to engage the concave member to effect weft parting, the second member being elongated in the direction of the advance of the shuttle, a holder for the second member with respect to which the latter is movable in all angular directions, a resilient element to maintain the second member in normal position, said second member being movable with respect to the holder when engaging the concave member to accommodate a different position of the shuttle, the resilient element consisting of a compression spring and the holder being tubular to guide the spring.

In testimony whereof I have hereunto affixed my signature.
